BURN-IN ATTACHMENT FOR MAINTAINING ROTARY FURNACE HEARTHS Robert E. Buckholdt, Salem, Ohio, assignor to
Edgar Homer Kendall

Application March 15, 1956, Serial No. 571,823

2 Claims. (Cl. 263—28)

This invention relates to the furnace art and more particularly to improved apparatus for establishing and maintaining prepared load-bearing surfaces on movable hearths in heating furnaces of the kind used to heat metal billets, for example, prior to forming and rolling operations. Because of the substantially high temperatures normally required in such furnaces and the necessity of protecting the supporting structure of the hearth from such high temperatures, it is now common practice to provide the upper load-bearing surface of such hearths with a layer of sintered chrome ore, for example, which when properly prepared forms an insulating refractory base of sufficient mechanical strength to support heavy billets and other metal objects on the hearth. Such preparation requires the heating of the chrome ore or other ceramic material herein generically referred to as chrome ore applied to the hearth to a sintering temperature of the order of 2700 degrees Fahrenheit to thereby solidify the pulverulent ore thereby increasing its load-bearing potential at lower temperatures while providing a refractory layer for heat insulation purposes.

Although the resulting chrome ore hearth has been found very desirable and advantageous in the furnace art, being generally accepted, its use and preparation does give rise to several perplexing problems which have heretofore been unsolved by the prior art. Although the burn-in temperature required for the chrome ore is far above that required during normal heating operations in the furnace, the common prior art practice has been to utilize the heating furnace proper for the burn-in process. When burning-in a new charge of chrome ore on the hearth, the furnace must therefore be overheated for sustained periods of time, causing scoring and damage to the insulating material of the heating chamber. This damage requires the rebuilding of the furnace chamber more often, thus resulting in increased cost of operation. Also, to secure the required higher temperature potential in the furnace, larger and more costly burners and other auxiliary equipment are required.

It is therefore the primary object of this invention to provide improved apparatus for burning-in chrome ore hearth tops in movable hearth furnaces directly in the furnace proper without overheating the entire furnace assembly and subjecting the various parts thereof to the elevated temperatures required for the burning-in process. In carrying out the above stated object I provide an assembly which is adapted to fit in the furnace in a direction transverse to the movement of the hearth and which has a plurality of downwardly directed high thermal release burners aligned above the chrome ore top of the hearth.

When the attachment is energized the newly added chrome ore on the hearth directly thereunder is heated to the elevated temperatures required for a desired period of time and then another section of the hearth is moved under the burners for proper heating. In this manner the entire surface of the chrome ore may be heated in successive steps to obtain the desired hearth condition.

Another object of the invention is the provision of a

2

burn-in attachment unit which may be adapted for use with hearth furnaces already in use to prepare the chrome ore. It is contemplated that the furnace assembly will not have to be modified in any appreciable way in accomplishing this objective.

While the applicability of this invention is not necessarily limited to rotary hearth furnaces, it is particularly advantageous for such use since the hearths in such furnaces must necessarily be assembled and built up directly in the annular heating chamber of the furnace structure and, of course, is not removable therefrom. Thus, if the intended service of such furnace is such as to require a burned-in hearth surface, such burning-in must take place directly in the furnace chamber, requiring the furnace to be operated, during the burning-in period, at temperatures considerably higher than normal operating temperatures.

These, as well as other objects and advantages of the invention will become apparent upon consideration of the following detailed specification and accompanying drawings wherein there is specifically disclosed apparatus for burning-in chrome ore hearth tops in movable hearth furnaces constructed in accordance with my invention.

In the drawing:

Figure 1 is a plan view of a rotary furnace utilizing the burn-in attachment constructed in accordance with the teachings of my invention;

Figure 2 is a vertical section taken along the sectional line 11—11 of Figure 1;

Figure 3 is a partially cut away side view of the burner attachment used in the furnace; and

Figure 4 is an end sectional view taken along the section line IV—IV of Figure 3.

Referring now to the drawing, and initially to Figure 1 thereof, there is shown a plan view of a rotary hearth furnace, designated generally by the numeral 10, having a chrome ore topped hearth and utilizing the burn-in attachment 41 of this invention. According to well known construction in the furnace art, the furnace 10 is circular in plan—having a cylindrical inner side wall 11, a similar outer side wall 12, and an annularly-shaped roof spanning the concentric side walls. Positioned within the side walls 11 and 12 is the annular hearth assembly 14 suitably supported for rotative movement about its own center which center is coincident with the centers of the side walls 11 and 12. Adjacent openings 15 and 16 are provided in the outer side furnace wall 12 to allow the metal objects to be heated to be moved into and out of the furnace, respectively.

Now referring to Figure 2 of the drawing, the rotary furnace 10 is built up between two concentric series of buckstays 17 the function of which is to provide vertical and lateral support for the side walls 11 and 12. A circular channel 18 is secured to the inner surface of the outer ring of buckstays 17 and this, together with the multiplicity of circularly and vertically arranged members 19, supports the side walls of the furnace 10. The furnace hearth assembly 14 is preferably constructed of hard refractory brick leaving a circular recess 20 in the top surface thereof which is filled with chrome ore 21 prepared in a manner to be hereinafter more fully described to form the load-supporting hearth of the furnace. The hearth assembly 14 is supported on a suitable structural steel platform 22, the latter being carried by a number of wheels 23—24 traveling on the rail circles 25—26. Rails 25—26 are supported on a suitable framework 27, the latter as well as the entire furnace assembly, being supported on a concrete base 28. Suitable mechanism (not shown) is employed to rotate the hearth assembly 14 within the furnace at the controlled rate of speed and to start and stop such rotation.

Evenly spaced about the entire periphery of both the inner and outer side walls 11 and 12, respectively, are

the fuel burners 29 for burning gaseous fuels to elevate the furnace chamber to the desired temperatures for heating metal objects. The fuel and compressed air necessary for efficient combustion is supplied through the circular conduits 30 and 31, respectively, carried adjacent the rings of buckstays 17 on the supports 32. Suitable means for connecting the individual burners 29 to the conduits 30 and 31 (not shown) are provided.

To properly exhaust the fumes from the furnace, the passageways 33 which open in a space within the furnace and which communicate with the concentric manifolds 34 positioned directly above the side walls 11 and 12 are provided. As indicated in Figure 1, the manifolds 34 are connected through conduit 35 and a power driven exhausting fan 36 to the stack 37.

The hearth assembly 14 is sealed from below by sand seals which consist of quantities of sand in the circular channels 38 and the cylindrically formed plates 39, the lower ends of which extend down into the sand carried by channels 38. Plates 39 are secured to the sides of the hearth assembly 14 and inasmuch as they are circularly concentric with the channels the seals are effectively maintained even during travel of the hearth assembly.

The above construction is well known in the furnace art to be an expedient heating furnace. Metal objects to be heated are loaded through the opening 15 onto the chrome ore hearth 21 and the hearth assembly 14 is rotated at the desired speed to allow the objects to obtain the correct temperature due to the heat liberated from the burners 29. After the hearth assembly 14 has traveled in a complete circle the heated objects are removed through the opening 16 and may be delivered for further operations to other apparatus, not shown. It is contemplated that vertically slidable doors 40 on the outer ring of the buckstays 17 will be closed when the loading and unloading of the furnace has been completed to prevent the loss of heat.

As indicated in the previous discussion the preparing of the chrome ore hearth in such a furnace as described above presents various and objectionable problems. To overcome these undesirable features I provide a new and novel burn-in attachment for the furnace 10 designated generally by the reference numeral 41. As shown in Figure 2, the burn-in attachment 41 is adapted to fit through the loading opening 15 and extend transversely across the hearth assembly 14 so that when the hearth is rotated about its axis the entire chrome ore hearth 21 is caused to pass under it. To support the burn-in assembly 41 I provide a shoulder 42 on the inner furnace wall 11 directly opposite the opening 15 which one end of the burn-in attachment rests on while the other end is supported by a suitable removable brick support 43 on the lower sill of the charging opening 15.

In Figures 3 and 4 of the drawing the burn-in attachment 41 is shown to consist of the rectangular structural steel frame 44 being of such length to extend between the side walls 11 and 12 of the rotary furnace 10. An inverted U-shaped jacket 45 forms the sides and top of the burn-in unit and is secured by the angles 46 to the structural frame 44. The top and sides 45 not only serve to add rigidity to the burn-in attachment structure but also are adapted to carry suitable means, such as the tubes 56, for circulating cooling fluid in the jacket 45 which precludes the need of refractory or insulating lining on the top and side walls of the assembly and further protects the heating chamber of the furnace as will be hereinafter more fully described.

The structural frame 44 also serves as a support for the plurality of aligned burners 47 directed downwardly toward the hearth assembly 14. The burners 47 are surrounded by the solid refractory fire brick partition 48 which is attached to the frame 44 and extends below the burners. Circular recesses are provided in the fire brick 48 thereby forming burner ports 49 through which the nozzles 50 of the burners 47 protrude. As is common

practice, the burner ports 49 increase in cross sectional area in the direction of flame propagation. It is contemplated that the burners 47 will be of the high thermal release type and in the illustrated embodiment these are depicted as utilizing fuel supplied through the conduit 51 while compressed air, necessary for efficient combustion, is carried in the conduit 52. These conduits 51 and 52, run the length of the burn-in attachment 41 and are surrounded on three sides by the jacket 45. Suitable conduits 53 and 54, made from standard pipe fittings, are tapped into the air and fuel conduits 51 and 52, respectively, and are provided to communicate and deliver the fuel and compressed air to the burners 47. It is understood, of course, that the conduits 51 and 52 are connected to adequate supplies of fuel and air (not shown) by suitable means.

In the operation of the burn-in attachment 41 for preparing and burning-in the chrome ore hearth of a rotary furnace, it is assumed that the pulverulent chrome ore has been added to the hearth where a new refractory surface is desired. After this preparatory operation the burn-in attachment 41 is pushed through the opening 15 until one end thereof rests on the shoulder 42 and the other end is supported by the fire brick block 43 on the sill of the charging opening. At this time the fuel and air supply conduits 51 and 52 are connected to their respective sources as well as the water jacket conduits to the supply of coolant.

The main furnace chamber is then heated to the maximum temperature encountered in heating metal workpieces passing through the furnace and after an interval of time the chrome ore will have obtained this temperature although no transformation will have taken place as these temperatures are usually not high enough to bring about the desired condition in the chrome ore. When the ore has obtained these temperatures the burn-in unit burners 47 are ignited and due to their positioning directly above the hearth, the configuration of the ports 49 and the refractory fire brick 48, the heat liberated therefrom is directed and deflected downwardly on a portion of the pre-heated chrome ore. The burners 47 are of the high thermal release type and are operative to give off enough heat to complete the high temperature transformation of the chrome ore hearth. As one section of the hearth obtains the desired condition of a hard refractory surface, the hearth assembly 14 may be rotated to bring another portion of the chrome ore under the burners for the burning-in process, this series of operations being continually repeated until all of the desired chrome ore has been transformed.

As an example, a rotary furnace installation might be used for heating metal blanks prior to further forming operations to a temperature of 2400 degrees Fahrenheit while chromie ore requires a temperature of 2700 minimum degrees Fahrenheit for the sintering process to take place. In this instance, the main heating chamber would be brought to a temperature of 2400 degrees and the attachment operated to raise the temperature of the chrome ore directly thereunder to that required to obtain the desired conditions.

In order to protect the structural frame of the attachment, as well as the body portion of the burners 47 and the conduits 51 and 52, coolant is circulated through the tubes 56 thereby substantially isolating these members from the intense heat.

When the entire hearth has been prepared, or a particular portion thereof as desired, the attachment 41 may be retracted and the furnace is ready to resume normal operations of heating metal workpieces. It should be understood, however, that it is possible, and sometimes preferable, to construct the burn-in attachment as an integral part of the furnace and this can be accomplished by providing a separate opening in the side wall 12 instead of utilizing the loading or unloading openings 15 and 16 with the attachment unit sup-

ported above the hearth far enough to allow headroom for passage of metal objects through the furnace. In this manner the operation of initially positioning and retracting the burn-in attachment each time it is needed is precluded. It may also be desirable to position the burn-in furnace between the loading and unloading entrances to the furnace thus separating them by a small distance and also making it possible to burn-in the chrome ore while the furnace is still being used to carry metal objects in a continuous manner through the heating chamber. The burning-in takes place in this case at a position where there is nothing on the hearth but the rest of it may be utilized for carrying metal workpieces. This type of installation is particularly attractive for use with a hearth where the furnace installation is an integral part of a process line and it is undesirable to stop production for burning-in the chrome ore hearth.

It should thus be apparent that I have accomplished the objects initially set forth by providing improved apparatus for burning-in chrome ore hearth tops in movable hearth furnaces directly in the furnace proper without overheating the entire furnace assembly. The invention teaches means for applying the desired temperature potential to a relatively small portion of the hearth, thus reducing the number or size of the burners employed in the main heating chamber.

It is further observed that although this apparatus is especially useful in the rotary type furnace or other furnaces where the hearth may not be removed from the main heating chamber, that the apparatus may be employed in any furnace structure having a movable hearth.

Another important feature of the invention is the provision that the burn-in attachment is adaptable for use with furnaces already in operation with only minor alterations and modifications to the furnace assembly. A shoulder must be built on the inner wall of the furnace and, depending upon the type of operation desired, an opening provided in the outer wall between the loading and unloading doors.

Although I have accomplished the objects initially set forth and described a specific embodiment of my invention, it should be understood that certain changes may be made therein without departing from the scope or intent of the invention and reference should therefore be had to the following appended claims in determining the complete coverage of the invention.

I claim:

1. In a combination a rotary furnace having concentric inner and outer spaced side walls, an annular roof joining said side walls, an annular hearth having a refractory upper load bearing surface received between said spaced side walls, means to move said annular hearth, said side walls, roof and hearth defining an annular heating chamber, a plurality of fuel burners disposed along said side walls of said heating chamber for heating said chamber during normal operations thereof, at least one opening in said outer spaced side wall for providing access to said heating chamber, a burn-in attachment for preparing and maintaining said refractory surface of said hearth, said burn-in attachment having an elongated rectangular structural framework, a layer of heat insulating refractory material attached to and depending from said framework, said layer having a plurality of burner ports therein, a plurality of high

thermal release burners mounted from and along the length of said framework with the nozzles thereof protruding through said ports, a fuel conduit positioned above and extending the length of said framework, a plurality of individual conduits connecting said fuel conduit and said last mentioned burners, said burn-in attachment being removably received within said opening in said outer side wall and extending in spanning relation between said inner and outer side walls across said movable hearth, said inner wall having a ledge thereon opposite said opening and supporting the end of said attachment, and said burner ports and high thermal release burners being closely adjacent said refractory surface of said annular hearth for heating that portion of said refractory surface directly thereunder to a desired degree higher than the normal operating temperatures of said furnace without overheating the entire heating chamber.

2. In combination a furnace having spaced side walls, a roof joining said spaced side walls, a hearth having a refractory load bearing surface received between said spaced side walls, means to move said hearth, said side walls, roof and hearth defining a heating chamber, a plurality of fuel burners disposed along said side walls of said heating chamber for heating said chamber during normal operations thereof, an opening in one of said side walls for providing access into said heating chamber, a burn-in attachment for preparing and maintaining said refractory surface of said hearth, said burn-in attachment having an elongated structural framework, a layer of heat insulating refractory material attached to and depending from said framework, a plurality of high thermal release burners mounted from and along the length of said framework with the nozzles thereof protruding through said layer, a fuel conduit positioned above and extending the length of said structural framework, a plurality of individual conduits connecting said fuel conduit with said last mentioned burners, an elongated jacket of U-shaped cross section having its ends attached to and generally coextensive with said elongated structural framework, said jacket and said framework defining an enclosed hollow portion above said layer, said fuel conduit being mounted within said hollow portion, means to circulate coolant within said hollow portion, said burn-in attachment being removably received within said opening in said one of said side walls and extending in spanning relation across said hearth, the other side wall having a ledge thereon opposite said opening for supporting the end of said burn-in attachment, and said high thermal release burners being closely adjacent said hearth for heating that portion thereof directly thereunder to a desired degree appreciably higher than the normal operating temperatures of said furnace without overheating the entire heating chamber.
